UNITED STATES PATENT OFFICE.

THOMAS G. BOWERS, OF NEW HAVEN, CONNECTICUT.

SHOULDER-BRACE.

1,093,379.

Specification of Letters Patent.

Patented Apr. 14, 1914.

Application filed April 10, 1913. Serial No. 760,209.

To all whom it may concern:

Be it known that I, THOMAS G. BOWERS, a citizen of the United States, residing at New Haven, in the county of New Haven 5 and State of Connecticut, have invented a new and useful Improvement in Shoulder Braces; and I do hereby declare the following, when taken in connection with the accompanying drawings and the characters of 10 reference marked thereon, to be a full, clear, and exact description of the same, and which said drawings constitute part of this application, and represent, in—

Figure 1 a rear view of a shoulder brace 15 constructed in accordance with my invention. Fig. 2 a detached view of one section with the ends of the armhole section broken away.

This invention relates to an improvement 20 in shoulder braces, and particularly to braces which comprise two sections provided with arm-holes and connected together by a series of lacings, the ends of which are attached to the end of belt straps. These 25 shoulder braces are preferably formed from comparatively light weight cloth and are subject to considerable strain.

The object of this invention is to provide 30 a reinforce for the body portion; and the invention consists in the construction hereinafter described and particularly recited in the claims.

In carrying out my invention, I employ 35 two back-sections 2, 3, preferably connected together at their lower edge by a binding 4 and provided at their adjacent edges with lacing strips 5 formed with eyelets 6 through which lacings 7 are passed. The ends of 40 these lacings are respectively secured to the ends of belt straps 8 and 9 the free ends of which are secured together in the usual way. Each section is provided with an armhole 45 formed by an extension 10 from the upper edge of each section, and an underarm extension 11 continuing from the lower edge of each section. The outer ends of these sections are connected together so as to complete the armhole. Extending from the lacings 50 strips 5 and 6 and starting preferably about midway thereof, are reinforcing stays 12 and 13. The upper edges of these stays extend in a slightly curved line from the lacings strips to the armholes, while the lower edges extend in a curved line into 55 the lower edge of each back-section at a

point below the armhole partially around which the stay extends. Preferably and as shown, belt-retaining loops 14 and 15 will be provided, these loops extending from the lower edge of the stays to the lower edge of 60 the back-sections parallel with the lacing strips and free except at their ends so as to provide loops beneath which the belt straps 8 and 9 extend. By providing reinforcing stays 12 and 13 as shown, two thicknesses 65 of material are provided at the point where the greatest strain occurs; or, in other words, transmit the strain imposed by the arm straps to the lacing strips, thus allowing the remaining portion of the braces to be 70 formed from comparatively light material.

I claim:—

1. A shoulder brace comprising two back sections each including an arm hole, said sections provided at their adjacent edges 75 with lacing strips, lacings extending from said strips, belts with which the respective ends of the lacings are connected, and reinforcing stays connected with said back sections and extending at their upper edges 80 from the lacing strips forward to the rear of the arm holes and at their lower edges from the said lacing strips forward and downward to the lower edge of said sections beneath said arm holes said reinforces 85 also extending forward and upward in front of the arm holes.

2. A shoulder brace comprising two back sections each including an arm hole, said sections provided at their adjacent edges 90 with lacing strips, lacings extending from said strips, belts with which the respective ends of the lacings are connected, reinforcing stays connected with said back sections and extending from the lacing strips forward and downward to the lower edge of 95 said sections beneath said arm holes, said reinforces also extending forward and upward in front of the arm holes, and loops extending from said stays to the lower edges 100 of the sections forward of the lacing strips, and substantially parallel therewith.

In testimony whereof, I have signed this specification in the presence of two subscribing witnesses.

THOS. G. BOWERS.
